(57) **CLAIM**

The ornamental design for a mortiser with dual ram fence, as shown and described.

DESCRIPTION

FIG. 1 is a front perspective view of the mortiser with dual ram fence of the present invention;

FIG. 2 is a rear perspective view;

FIG. 3 is a front elevation view;

FIG. 4 is a right side elevation view;

FIG. 5 is a left side elevation view;

FIG. 6 is a rear elevation view;

FIG. 7 is a top plan view;

FIG. 8 is a bottom plan view; and,

FIG. 9 is a front perspective view.

The broken line showing of a mortising bit, clamps, and tools in FIG. 9 is for illustrative purposes only and forms no part of the claimed design.
